Primary Examiner—Alan P. Douglas*Assistant Examiner*—Antoine D. Davis*Attorney, Agent, or Firm*—John Edward Roethel[57] **CLAIM**

The ornamental design for a tire repair work station, as shown and described.

DESCRIPTION

FIG. 1 is an isometric view of the tire repair work station showing my new design, with a tire shown in broken lines. The broken line showing of the tire is for illustrative purposes only and forms no part of the claimed design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.
